United States Patent Office

Des. 221,086
Patented July 6, 1971

221,086

STAND FOR A COMPUTER PRINTER

Gregory F. Fossella, Marshfield, Mass., assignor to Nortec
Computer Devices, Inc., Ashland, Mass.

Filed Nov. 26, 1969, Ser. No. 20,283

Term of patent 14 years

Int. Cl. D6—01

U.S. Cl. D33—3

FIG. 1.

FIG. 2.

FIG. 3.

FIG. 1 is a perspective view of the stand for a computer printer showing my new design;

FIG. 2 is a reversed axonometric view of the stand of FIG. 1; and

FIG. 3 is a side elevation view of the stand of FIG. 1.
I claim:

The ornamental design for a stand for a computer printer, substantially as shown.
